KATHRYN DOROTHY HARDING, OF EVANSTON, ILLINOIS.

ATTACHMENT FOR CRUTCHES.

1,003,103.

Specification of Letters Patent. Patented Sept. 12, 1911.

Original application filed April 24, 1908, Serial No. 429,068. Divided and this application filed December 16, 1908. Serial No. 467,899.

To all whom it may concern:

Be it known that I, KATHRYN DOROTHY HARDING, a citizen of the United States, residing in Evanston, county of Cook, State 5 of Illinois, have invented a certain new and useful Attachment for Crutches, of which the following is a specification.

My invention relates to that class of devices which are designed to prevent the 10 crutch or crutches from slipping when they are used on ice or on other slippery places, and which may be put in or out of use at the will of the user without the necessity of removing the crutch from the arm-pit.

15 My invention has for its object to provide a simple and inexpensive form of attachment which may be used upon the ordinary crutches which are now on the market, with very little change. Similar forms of 20 accomplishing this result with which I am familiar are arranged so that the point of the rod is held by a spring normally in a retracted position and when it is advanced beyond the tip of the crutch by the engagement 25 of a shoulder on the rod. This taking place upon the rod being moved laterally in the crutch through the slot formed in a metal plate attached to the cross piece. Practice has shown that where any degree 30 of weight is placed upon the point of the rod, it serves frequently to dislodge the shoulder from engagement with the plate and the spring instantly retracts the rod to its normal position, permitting the crutch 35 to slip and frequently causes severe falls.

My invention is designed to provide a rod which is held projected, both by a spring and by a positive lock, and cannot be retracted except the rod be rotated by the user 40 of the crutch.

45 My means of accomplishing the foregoing may be more readily understood by having reference to the accompanying drawings which are hereunto annexed and are a part of this specification; in which—

Figure 1, shows my improvement applied to a crutch. Fig. 2, is a cross section taken on the line X X in Fig. 3. Fig. 3, is an enlarged detail view of my device. Fig. 4, is a 50 cross section taken on the line a a in Fig. 3.

Similar reference numerals refer to similar parts throughout the entire description.

As shown in the drawings, the crutch is provided with arms 1 and 2, a concave top-

piece 3, a cross-piece 4 for the hand rest, 55 and a tip 5. As far as described the crutch is of the usual and ordinary construction.

My improvement, as more clearly shown in the detail view, consists of a rod 6 carried in suitable bearings 7 and 8. The rod 60 6 is projected downwardly through the central portion of the tip 5, and the lower end of the rod 6 is sharpened and adapted to engage the surface upon which the user is walking. The bearing 8 is formed, as better shown in the detail view, with a slot 9 extending laterally from the opening 10 through which the rod 6 passes, the bearing member is cast or formed in a single piece, and is detachably secured to the crutch by 65 screws (not shown). This construction enables my attachment to be placed on any crutch by drilling a small hole through the tip thereof. The slot 9 is fitted to a pin 11, which is fixedly mounted upon the rod 6. 70 A coil spring 12 is provided, exerting a tension to project the rod 6 downwardly, the locating of the spring 12 is of importance for two reasons. First, because when located adjacent the ground, the tip being constantly used in snow and ice, the spring 75 rusts quickly and becomes inoperative by reason of a permanent set, or is so weakened by the rust as to be useless, and for the further reason that locating it as I do, obviates the necessity of drilling a recess in the tip of the crutch, hereby weakening it, as the recess has to be of considerable size in order to hold a spring of sufficient 80 strength to do the work. A handle 13 is 85 suitably secured to the top of the rod 6 to enable the operator to adjust the position of the rod 6.

The operation of this device is as follows:—When the user is walking upon a 95 slippery surface or one where the need of a device of this character is felt, he turns the handle 13, which obviously may be of any desired form until the pin 11 is in register with the slot 9. The tension exerted by 100 the coil spring 12 will operate to project the point of the rod 6 beyond the tip 5 of the crutch, when a slight rotation of the handle 13 will move the pin 11 out of register with the slot 9, causing it to engage the lower end 105 of the bearing 8, which effectually prevents its retraction, while it will be obvious from the above description that when it is desired

to retract the point of the rod 6, a slight movement of the handle will be sufficient to bring the pin 11 again in register with the slot 9, when the rod 6 may be lifted until the pin is above the bearing 8, at which point continued rotation of the handle will place the pin out of register with the slot, and the sharpened end of the rod 6 will be held out of engagement with the surface which is being walked upon.

Although I have shown and described a specific form of utilizing my invention, many changes will suggest themselves to persons skilled in the art, which will fall within the scope of my invention as claimed.

Having described my invention what I regard as new and desire to secure by Letters Patent is:—

The combination with a crutch, having a small central vertical opening through its tip, a rod slidably mounted in said opening, the lower end of said rod being pointed, a

handle set against its upper end adjacent the crutch, a bearing member, having tapering side walls and cross connectors, detachably secured to the crutch adjacent the cross bar, bearings formed in said cross members, there being a slot formed in the lower cross connector extending laterally from the bearing formed therein, a pin projecting from one side of the rod adapted to register with the said slot, a coil spring located intermediate the cross connectors of the bearing members, a pin holding said spring in place, said spring exerting a tension to project the point of the rod beyond the tip of the crutch when the first named pin is in register with the slot for the purpose set forth substantially as described.
